Primary Examiner — Elizabeth J Oswecki(74) *Attorney, Agent, or Firm* — Stephen Kenny; Walter M. Egbert, III; Foley Hoag LLP(57) **CLAIM**

The ornamental design for a boat for a deposition apparatus, as shown and described.

DESCRIPTION

FIG. 1 is a perspective view of a boat for a deposition apparatus showing our new design;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is another side view thereof.

Broken lines are used in the drawings to illustrate features that form no part of the claimed design.
